UNITED STATES PATENT OFFICE.

ARTHUR E. FOLSOM, OF WINCHENDON, MASSACHUSETTS, JOHN H. VINTON, OF KEENE, NEW HAMPSHIRE, AND WILLIAM M. WHITNEY, OF WINCHENDON, MASSACHUSETTS, ASSIGNORS, BY MESNE ASSIGNMENTS, TO UNITED SHOE MACHINERY CORPORATION, OF PATERSON, NEW JERSEY, A CORPORATION OF NEW JERSEY.

MACHINE FOR SHAPING WOODEN HEELS.

Application filed July 22, 1920. Serial No. 398,183.

To all whom it may concern:

- Be it known that we, ARTHUR E. Folsom, a citizen of the United States, residing at Winchendon, in the county of Worcester and State of Massachusetts, JOHN H. VINTON, a citizen of the United States, residing at Keene, in the county of Cheshire and State of New Hampshire, and WILLIAM M. WHITNEY, a citizen of the United States, residing at Winchendon, in the county of Worcester and State of Massachusetts, have invented new and useful Improvements in Machines for Shaping Wooden Heels, of which the following is a specification.
- 15 This invention relates to a machine for shaping wooden heels, the object of the invention being to provide a practical machine which will accurately and smoothly shape a heel from a block of wood and which is so constructed that heels of different shapes and sizes may be shaped upon the same machine.

Heretofore machines for cutting wooden heels have always developed objectionable vibration of the trimming cutters. In the use of such machines under the present practice, a wooden heel blank is held in a jack moved by the operator against a guide, and is operated upon by the periphery of a rotary cutter, so that even slight cutter vibration produces an irregular surface on the heel. Heretofore such machines have been driven from factory shafting by belt gearing which necessarily exerts a side pull on the cutter shafts tending to induce irregular cutter action. Moreover, belt bearing is characteristically liable to develop uneven or whipping action due to irregularities produced by the belt lacing or otherwise, or because a belt pulley is out of true, wobbles, or is for any other reason unbalanced. Then, too, in view of the heavy duty imposed, such a machine requires that the belting be unusually tight to maintain sufficient traction, and this results in rapid wear of the cutter shaft and its bearings, with the necessity of frequent renewal of the shaft bushings. By reason of the further fact that such trimming cutters commonly run at very high speeds such as 5000-6000 revolutions per minute, the above referred to and other similar conditions are very much aggravated,

with the result that for one reason or another it is difficult and often practically impossible to maintain the cutters free from harmful vibration and to produce satisfactory heel cutting even with the most painstaking and skillful work on the part of an operator.

High as is the speed indicated, it has been found that a substantial increase in it would greatly improve the quality of work produced if it could be obtained without further aggravating the conditions above noted. The beginning of the cut at the breast of a wooden heel is somewhat against the grain of the wood, and the heel is often injured by forcing it too rapidly into the cutter at this point. We have found that a cutter speed of 7000 R. P. M. or thereabouts permits as rapid a feed as any operator can be expected to produce, without tearing out splinters near the breast. This speed, however, has not proved practically feasible for a belt driven cutter.

Improper heel cutting results either in making the product unsalable, or requires expensive hand finishing to repair the damage as well as possible.

In view of the foregoing, it is an object of the present invention to provide a heel cutting machine, the operating mechanism of which is so organized that it may be depended upon to operate practically without vibration, and which will be free from belt troubles and excessive wear and tear resulting therefrom, and economical and reliable to maintain and operate in this and other respects.

In the attainment of this object, the present invention provides a novel organization comprising, as herein illustrated, a rotating cutter having its periphery formed to trim the edges of wooden heel blanks, which cutter is carried on a shaft driven by a high speed motor having its rotor mounted directly on the shaft concentrically therewith. In this construction, the cutter shaft constitutes the rotor shaft of the motor, and it is not only practicable to balance the moving parts of the machine with extreme accuracy, but in the operation of the machine there is no force other than the pressure of the work against the cutter tending to throw the rotat-

ing parts of the machine out of balance. Consequently, not only is undesirable cutter shaft vibration minimized, but the wear on the bearings and shafts is so slight as to be negligible even over a long period, and at the same time, a speed of 7000 R. P. M. or even higher can be readily maintained.

The novel block holder we have shown in this application is in itself an invention of 10 John H. Vinton, one of the applicants in this case, for which he has applied for United States Letters Patent on "Block holder for heel turning machines," filed March 27, 1920, Serial No. 369,437, but this 15 invention is not restricted to any particular form of block holder as the invention broadly resides in a novel organization comprising the combination of an electric motor including a spindle, a cutter fast to said 20 spindle and a holder for a wooden heel block which is adapted to be moved relatively to said cutter in order that it may be shaped to form a wooden heel. In the machine disclosed two cutter spindles are employed rotating in opposite directions, one of said 25 spindles, when looking down upon the same, being rotated in a clockwise direction and the other in a counterclockwise direction.

The invention further consists in certain 30 detailed constructions and combination of parts all as hereinafter fully set forth in the specification and particularly pointed out in the claims.

Referring to the drawings:—

35 Figure 1 is a front elevation of our improved machine for shaping wooden heels.

Fig. 2 is a side elevation of the same as viewed from the left of Figure 1.

Fig. 3 is a sectional elevation taken on the 40 line 3—3, Figure 1.

Fig. 4 is a plan view of the machine.

Figs. 5 to 10 inclusive are diagrammatic 45 plan views illustrating the different positions which are assumed by the block holder and its former relatively to the rotary cutters.

Like numerals refer to like parts throughout the several views of the drawings.

In the drawings, 15 is the frame of the 50 machine. 16 is one of the motors and 17 the block holder. The motor 16 consists of the usual stator 18 and rotor 19, which is fastened to a vertical spindle 20 to the upper end of which is clamped a pair of cutters 21 by means of collars 22 and 23 and a nut 24, 55 which has screw-threaded engagement with the upper end of the spindle 20. The spindle 20 has two conical portions 25 and 26 which are rotatably mounted in bearings 27 and 28 respectively. These bearings are slidably 60 mounted upon the frame 15 and are clamped in position on said frame by bolts 29 and 30. The bearings 27 and 28 are connected together by a vertical shaft 31 which is fastened at its upper end by a set screw 32 to a depending bracket 33 on the bearing 27 and is

fastened at its lower end by a set screw 34 to an upwardly projecting bracket 35 on the bearing 28.

The motor is provided with a casing which encloses the stator and rotor and a portion of the spindle and this casing consists of an upper cap 36 and a lower cap 37 which are both fastened to a supporting member 38 which projects rearwardly from the motor and has an ear 39 thereon which is fastened by set screws 40 and 41 to the stationary vertical shaft 31. 70

It will thus be seen that the upper bearing 27, the lower bearing 28 and the motor 16 are all connected together by the vertical shaft 31 and these parts may be adjusted vertically and simultaneously by means of a screw 42 which bears against the under side of the bearing 27, see Figs. 1 and 3, and has screw-threaded engagement with a portion of the frame. The lower bearing 28 is provided with a bushing 43 which may be adjusted vertically in the bearing by means of collars 44 and 45, Fig. 3. Said bushing is provided with an oil chamber 46 and has attached to its lower end by screw-threaded engagement therewith a pedestal cap 47 which is locked in position upon the bushing 43 by a set collar 48. The lower end of the shaft rests upon a seat 49 which is loosely mounted upon the cap 47. The upper bearing 27 is also provided with oil chambers 50, it being very essential that the bearings of the spindle should be thoroughly lubricated in view of the high speed of rotation of the same. 80

The machine of our invention is provided with two motors 16 and 51 with two motor spindles 20 and 52 respectively, the different bearings and the construction throughout of these motors, their spindles and co-operating 105 parts being substantially the same, the spindle 52 having a pair of cutters 53 fastened thereto corresponding to the cutters 21 on the spindle 20 with this exception that the spindle 20, looking down upon the same, rotates in a counterclockwise direction, while the spindle 52 rotates in a clockwise direction. The reason for this being that the cutters on the spindle 20 shape one side of the heel and the cutters on the spindle 52 shape the 115 other side of the heel, it being necessary that the cutters should cut with the grain upon the opposite sides of the heel and this necessitates rotating the cutter spindles in opposite directions. 120

Since the holder for the block of wood does not per se constitute a portion of this invention and as the same is fully described in detail in said application for Letters Patent by said Vinton, it is thought unnecessary 125 to describe in detail said block holder as any suitable block holder may be employed in combination with a vertical electric motor spindle without departing from the spirit of this invention, but said holder consists 130

mainly of a support 54 for the block 55 the block being clamped in position upon said holder by a jaw 56 which is pivoted to a primary clamping lever 57, said primary 5 clamping lever being actuated by means of a secondary clamping lever 58 to which motion is imparted by a lever 59 pivoted at 60 to the frame 61 of the block holder. The frame 61 is pivoted at 62 to a holder 63 10 which is fastened to a vertical rock shaft 64. Said rock shaft is rotatably and slidably mounted in bearings 65 and 66 carried upon a swinging bracket or carrier 67, said swinging bracket being mounted upon a vertical 15 shaft 68 to which it is clamped by ears 69 and 70 and clamp screws 71 and 72 respectively. The ear 69 bears against the upper end of a bearing 73 for the shaft 68 mounted on the frame 15 of the machine. The lower 20 end of the shaft 68 is also suitably supported in a bearing. The lower end of the shaft 64 has an arm 74 fast thereto upon which is rotatably mounted a roller 75 which is adapted, in the operation of the machine, to 25 bear against the upper edge of a W-shaped cam track 76. This cam track is pivoted at its ends 77 to a bracket 78 on the frame and is adjusted to raise or lower the same more or less by means of an adjusting screw 79 30 which has screw-threaded engagement with the bracket 78 and the upper end of which bears against the under side of said cam track 76.

The cam track 76 and the bracket 78 are 35 adjustable together as a whole by means of screws 80 and 81, see Fig. 1, which have screw-threaded engagement with lugs 82 and 83 upon the frame of the machine, the upper ends of said screws bearing against depending slide members 84 and 85 which are 40 adapted to slide upon the frame 15 of the machine and are guided and clamped in position thereon by bolts 86 and 87 which project through slots 88 and 89 in said slide 45 members 84 and 85 and are fastened to the frame of the machine.

By means of the cam 76 a vertical motion is imparted to the block holder through the shaft 64. A tipping motion is imparted to 50 the block holder by a U-shaped cam track 90 against the upper edge of which a roll 91 mounted on the jack frame 61 bears during the operation of the machine. The cam track 90 is pivoted at its ends 92 to a bracket 55 93 and said cam track 90 is adjusted to different positions vertically by means of an 60 adjusting screw 94 which has screw-threaded engagement with the bracket 93 and the upper end of which bears against the lower edge of the cam track 90.

The bracket 93 together with the cam track 90 may be adjusted vertically by means of screws 95 which bear against depending arms 96 on the bracket 93 and have screw-threaded engagement with ears 97 on the

frame 15 of the machine. The bracket 93 is guided upon and clamped to the frame 15 of the machine by bolts 98 which are fastened to the frame of the machine and project through slots 99 in the depending arms 70 96. The height to which the bracket 78 is adjusted together with the cam track 76 is indicated by means of an index finger 100 fast to the frame 15 and a scale 101 fast to the depending arm 85, while the adjustment 75 of the bracket 93 and cam track 90 are indicated by an index finger 102 fast to the frame of the machine and a scale 103 fast to the depending arm 96.

A former 104 is fastened to the vertical 80 shaft 64 of the block holder and this former is adapted to engage, in the operation of the machine, either one of a pair of guides 105 or 106. These guides are duplicates of each other and are slidably mounted upon the 85 frame of the machine, being adjusted thereon by means of an adjusting screw 107 and clamped by means of clamp screws 108 to the frame 15.

The general operation of the mechanism 90 hereinbefore specifically described is as follows: The motors 16 and 51 are thrown into operation by a convenient switch not shown in the drawings thus causing the spindles 20 and 52 to rotate in the directions of the arrows *a* and *b* respectively. A block of wood is placed upon the support 54 and the handle of the lever 59 is then depressed causing the lever 58 and the primary clamping lever 57 to move 100 downwardly at their forward ends, thus causing the jaw 56 to be moved downwardly against the block 55 to clamp it against block holder coincides with the longitudinal median plane B—B, Fig. 5, of the 105 block holder coincides with the longitudinal median plane A—A of the swinging bracket 67.

The operator moves the block holder 17 and the parts supported thereon until the 110 center lines A—A and B—B of the swinging bracket and block holder respectively assume the relative positions illustrated in Fig. 6 with the former 104 in engagement with the guide 105 and with one side of 115 the block 55 in engagement with the cutter 21. The operator then turns the block holder and the swinging bracket counter-clockwise, the block 55 being held in engagement with the cutter 16 until the parts 120 arrive in the position illustrated in Fig. 7. During these motions the former 104 is held against the guide 105 and the frame 61 of the block holder is raised and lowered by means of the shaft 64, arm 74 and track 76 and is tipped upon its pivot 62 by means of the roll 91 and cam-shaped track 90 in order to produce the proper shaped contour for the heel of the shoe on one side 125 of the heel from the breast to the middle 130

of the back thereof. The operator having finished one side of the heel now moves the parts to the position illustrated in Fig. 8, which is the same as the position illustrated in Fig. 5 and then moves the parts until their center lines A—A and B—B assume the relative positions illustrated in Fig. 9 and finally to the position illustrated in Fig. 10, thus completing the shaping of the heel of the shoe. The parts are then moved back to the position illustrated in Fig. 5 and the lever 59 is raised thus releasing the heel of the shoe and allowing it to be removed by the operator from the block holder. In the described machine, the motors are run at about 7200 R. P. M. This speed enables the cutters to take small chips and to produce smooth work irrespective of the rapidity with which the operator forces the blank into the cutter. In the slower running machines of the prior art it has been necessary to feed the blank slowly into the cutter when cutting the surface near the breast where the cut is slightly against the grain.

We claim:

1. A machine for shaping wooden heels having, in combination, an electric motor including a rotary spindle, a cutter fast to said spindle, a bracket pivoted to swing on the frame of said machine, a holder for a block adapted to slide vertically upon said swinging bracket and a cam on said frame adapted to impart a reciprocatory vertical motion to said block holder.

2. A machine for shaping wooden heels having, in combination, an electric motor including a rotary spindle, a cutter fast to said spindle, a bracket pivoted to swing on the frame of said machine, a holder for a block adapted to slide vertically upon said swinging bracket, a cam on said frame adapted to impart a reciprocatory vertical motion to said block holder and means to raise and lower said cam.

3. A machine for shaping wooden heels having, in combination, an electric motor including a rotary spindle, a cutter fast to said spindle, a bracket pivoted to swing on the frame of said machine, a vertical shaft slidably mounted on said swinging bracket, a horizontal pivot movable with said vertical shaft, a block holder pivotally mounted to rock on said pivot, means to impart a vertical movement to said shaft and means to rock said block holder upon its pivot.

4. A machine for shaping wooden heels having, in combination, an electric motor including a vertical rotary spindle, a cutter fast to said spindle, a holder for a block, a bracket mounted to swing upon the frame of said machine and upon which said block holder is pivotally mounted, a former fast to said block holder, and a guide fast to

the frame of said machine and adapted to be engaged by said former whereby said block holder may be moved to so position said block relatively to said cutter that it may be shaped to form a wooden heel. 70

5. A machine for shaping wooden heels having, in combination, a pair of electric motors each including a rotary spindle, said spindles being adapted to rotate respectively in opposite directions, a cutter fast to each of said spindles, a bracket pivoted to swing on the frame of said machine, a holder for a block adapted to slide vertically upon said swinging bracket and a cam on said frame adapted to impart a reciprocatory 75 vertical motion to said block holder.

6. A machine for shaping wooden heels having, in combination, a pair of electric motors each including a rotary spindle, a cutter fast to each of said spindles, said spindles being adapted to rotate in opposite directions respectively, a bracket pivoted to swing on the frame of said machine, a holder for a block adapted to slide vertically upon said swinging bracket, a cam on said frame 80 adapted to impart a reciprocatory vertical motion to said block holder and means to raise and lower said cam.

7. A machine for shaping wooden heels having, in combination, a pair of electric 25 motors each including a rotary spindle, a cutter fast to each of said spindles, said spindles being adapted to rotate in opposite directions respectively, a bracket pivoted to swing on the frame of said machine, a vertical shaft slidably mounted on said swinging bracket, a horizontal pivot movable with said vertical shaft, a block holder pivotally mounted to rock on said pivot, means to impart a vertical movement to 100 said shaft and means to rock said block holder upon its pivot. 105

8. A machine for shaping wooden heels having, in combination, a pair of electric motors each including a vertical rotary 110 spindle, said spindles being adapted to rotate respectively in opposite directions, a cutter fast to each of said spindles, a holder for a block, a bracket mounted to swing upon the frame of said machine and upon which 115 said block holder is pivotally mounted, a former fast to said block holder and a stationary guide adjacent to each of said spindles respectively, said guides adapted to be engaged alternately by said former, whereby said block holder may be moved to so position said block relatively to each of said cutters that it may be shaped to form a wooden heel.

9. A machine for shaping wooden heels having, in combination, a frame, an electric motor including a rotary spindle mounted on said frame, a cutter fast to said spindle, a bracket pivoted to swing on said frame, a holder for a block adapted to slide vertically 125 130

upon said swinging bracket, an auxiliary frame, a cam pivotally mounted on said auxiliary frame and adapted to impart a reciprocatory vertical motion to said block holder, means to adjust said cam on said auxiliary frame and means to adjust said auxiliary frame vertically on said frame.

10. A machine for shaping wooden heels having, in combination, a frame, an electric motor including a rotary spindle mounted on the frame, a cutter fast to the spindle, a holder for a wooden heel block, a carrier on which the holder is pivoted for movement about two axes parallel to that of the spindle and perpendicular thereto respectively, arranged to hold a heel block on the holder in operative relation with the cutter while permitting relative to-and-fro movement of the holder and cutter to shape the heel as 15 the holder turns about its said parallel pivotal axis, and a cam for tilting the holder about the said perpendicular pivotal axis to govern the pitch of the heel being cut.

11. A machine for shaping wooden heels 20 having, in combination, a frame, an electric motor including a rotary spindle mounted on the frame, a cutter fast to the spindle,

a holder for a wooden heel block, a carrier arranged to carry a heel block on the holder into operative relation to the cutter, and on 25 which the holder has three species of movement; viz., first, a movement of translation parallel to the axis of the spindle; second, a movement of rotation about an axis parallel to that of the spindle; third, a movement of rotation about an axis perpendicular to that of the spindle: a guiding instrumentality located between the spindle and the holder for controlling the relative positions of the carrier and spindle as the 30 second described movement proceeds, to shape the heel; and cam mechanism for effecting the first and third described movements.

In testimony whereof we have hereunto 35 set our hands in presence of two subscribing witnesses.
